[57] CLAIM

The ornamental design for a recycling unit for waste
collection vehicle, as shown and described.

DESCRIPTION

FIG. 1 is a top plan view of a recycling unit for waste
collection vehicle showing our new design;

FIG. 2 is a right side elevational view thereof;

FIG. 3 is a front elevational view thereof;

FIG. 4 is a rear elevational view thereof;

FIG. 5 is a left side elevation viewed thereof;

FIG. 6 is a bottom plan view thereof; and,

FIG. 7 is a left side perspective view thereof, is being
understood that the broken lines are for illustrative
purposes only and form no part of the claimed design.
